UNITED STATES PATENT OFFICE

167,884

EXTENSION COMMODE

Harry B. Gaines, Chicago, Ill., assignor to Saginaw Furniture Shops, Inc., Chicago, Ill., a corporation of Michigan

Application January 31, 1951, Serial No. 14,050

Term of patent 14 years

(Cl. D33—6)

To all whom it may concern:

Be it known that I, Harry B. Gaines, a citizen of the United States, residing at Chicago, in the county of Cook, and State of Illinois, have invented a new, original, and ornamental Design for an Extension Commode, of which the following is a specification, reference being had to the accompanying drawing forming a part thereof.

In the accompanying drawing,

Fig. 1 is a perspective view of an extension commode showing my new design.

Fig. 2 is a perspective view of the commode in extended position.

The salient features of the design are most clearly delineated in that aspect of the commode appearing in Figure 2.

I claim:

The ornamental design for an extension commode, substantially as shown and described.

HARRY B. GAINES.
